(57) **CLAIM**

The ornamental design for a boot strap puller, as shown and described.

DESCRIPTION

FIG. 1 is a top perspective view of a boot strap puller secured to a boot;

FIG. 2 is a top perspective of the boot strap puller without the boot;

FIG. 3 is a top perspective view of the boot strap puller in a flat position;

FIG. 4 is a top view of the boot strap puller;

FIG. 5 is a bottom view of the boot strap puller;

FIG. 6 is a left side view of the boot strap puller;

FIG. 7 is a right side view of the boot strap puller;

FIG. 8 is a front elevational view of the boot strap puller; and,

FIG. 9 is a rear elevational view of the boot strap puller. The boot shown in broken lines in FIG. 1 is for illustrative purposes only and forms no part of the claimed design.
